UNITED STATES PATENT OFFICE.

SAM MENDEL, OF MANCHESTER, ENGLAND.

FASTENING FOR BROOCHES AND LIKE ARTICLES.

Application filed October 6, 1920. Serial No. 415,114.

To all whom it may concern:

Be it known that I, SAM MENDEL, a subject of the King of Great Britain and Ireland, residing at Manchester, in the county of Lancaster, England, have invented new and useful Improvements in Fastenings for Brooches and like Articles, of which the following is a specification.

This invention relates to fastenings for 10 brooches, safety pins and like articles and has for its object to provide an improved device for additionally securing the article in such a manner that if the main pin or fastening thereof breaks or becomes unfastened the article will still remain attached to the wearer and will, therefore, not be lost.

To this end according to the invention the device comprises a member secured at one end to the brooch or other article, its other 20 end being adapted to be detachably connected to the usual securing pin thereof after the latter has been passed through the material to which the article is to be secured.

In one suitable construction according to 25 the invention the device consists of a suitably bent wire, one end of which is attached to the usual hinged or spring securing pin of the article in any suitable manner, the other end being formed with a hook adapted to be hooked over the said pin thus forming a loop. A link attached to the article is passed on to the wire, the link being of such a size and so positioned on the article that the securing pin can be opened or 35 closed about its hinge in the usual manner.

With an article fitted with a device of this kind, to attach same to the wearer the hooked end of the wire is detached from the pin and the latter inserted in the clothing as usual, the hooked end of the wire is then replaced on the pin and the article is closed in the usual manner.

It will be obvious that with this arrangement should the article break away from its 45 pin either completely or at either end, then it will still be retained by the link working in the loop attached to the pin.

Various forms of the device may be constructed.

To enable the invention to be fully understood it will now be described by reference to the accompanying drawings, in which:

Figs. 1 to 5 are views in side elevation showing brooches provided with various 55 forms of the device constructed according to

the invention, the brooches being in the open or unfastened position.

Fig. 2^a is a side view of a modification of Fig. 2.

Fig. 6 is a side elevation showing a 60 brooch fitted with a device constructed according to one form of the invention, in the closed position and fastened to a piece of material, and

Fig. 7 is a similar view but showing the 65 brooch with the catch unfastened.

Fig. 8 is a side elevation showing a 70 brooch fastened to a piece of material and provided with a device according to one form of the invention, the brooch having 75 broken away completely from the usual securing pin.

Figs. 9 and 10 are side and plan views respectively, drawn to a larger scale, of a frictional locking plate which may be used for 75 securing the additional securing member to the brooch pin, and

Figs. 11 to 17 are side elevations showing the method of using the said locking plate.

In the form shown in Fig. 1, the brooch 1 having a hinged securing pin 2 is provided according to the invention with a loop 3 formed of wire, one end 4 being secured to the pin by twisting it tightly around same, the other end being formed with a hook 5 adapted to snap over the pin 2 near the end thereof. The end 4 is preferably formed with an additional coil or coils as shown to give spring to the wire. With this construction to attach the brooch the hook 5 is detached from the pin and the latter inserted in the material 6 (Fig. 6) in the usual way, the hook 5 is then snapped over the projecting portion of the pin and the brooch is fastened in the usual manner, the parts then being in the positions as shown in Fig. 6. Should the brooch then become unfastened the loop 3 still retains the brooch in the material as shown in Fig. 7.

Fig. 2 shows a modification in which a link 7 is attached to the brooch 1 near its hinge, said link having the loop 3 passed there-through. With this arrangement if the brooch breaks away at either end, or completely away from its pin as shown in Fig. 8, it is still retained on the loop 3 and thus is not lost. The link 7 may be so positioned and of such a size as to permit opening and closing of the brooch pin to the desired extent.

As a modification of the arrangement shown in Fig. 2, the wire loop 3 may be secured at one end to the brooch body and passed through an eye or the like secured 5 upon the securing pin, see Fig. 2^a.

In the construction shown in Fig. 3, the end 4 of the loop 3 is extended and provided with a sharpened portion 8 which is bent as shown to form an additional pin for entering the material to prevent drooping of the brooch. Fig. 4 shows the loop 3 formed of a wire having one end attached to a bush or sleeve 9 soldered upon the pin 2. Fig. 5 shows the loop 3 formed of a wire having one end pivotally attached to a split bush or sleeve 9 frictionally secured upon the pin 2.

Figs. 9 and 10 show a friction locking plate 20 drawn to a larger scale which may be advantageously employed for securing 20 the additional fastening member to the brooch pin as shown in Figs. 11 to 15 and Fig. 17. This plate 20 is curved as shown and provided with two holes 21 so that the plate can be passed on to the brooch pin, 25 the upturned ends 22 then bearing on the pin and holding said plate in frictional engagement with the pin.

In the form shown in Fig. 11, the wire loop 3 is shown secured to the pin 2 by 30 twisting one end round said pin.

It is difficult in practice to secure the loop effectively in this manner. If, however, the plate 20 is used, it is not necessary that the twisted end of the loop should be tight on 35 the pin. The twist may be formed in the loop and placed in the centre of the plate 20, and the brooch pin passed through the holes 21 and the twist, the plate frictionally locking on the pin and keeping the twist in 40 place.

Fig. 11 shows the plate 20 with the ends 22 bearing on the inside of pin 2.

Fig. 12 shows the plate 20 with the ends 22 bearing on the outside of pin 2, the loop 45 3 being brought through a hole in the plate.

Fig. 13 shows the plate 20 used with a flexible member 10 having the spring portion 11. In this case the securing ring 23 of member 10 may be a loose fit on the pin 50 2. The spring 11 is not essential, but would be preferably used.

Fig. 20 shows a further modification in which the ring 23 of the flexible member 10

is secured to the plate 14. In this case the centre of plate 20 may have a depression or 55 punched up portion in the walls of which holes are made through which the ring 23 may be passed. Or the centre of the plate may have an opening adapted to allow the flexible member to pass therethrough, said 60 member having a ring or stop on its end of sufficient size to be retained in the plate, thus securing said member to the plate.

Fig. 15 shows a modification in which a wire loop 3 is attached at one end to the 65 plate 20. The plate may be provided with side lugs adapted to be bent at right angles to the plate and having holes therein to receive the pivot of the pin, see Fig. 16, the plate being arranged on the pin the reverse 70 way to the plate shown in Fig. 15.

Fig. 17 shows a modification in which a figure of 8 loop 23 is held in position on the pin 2 by a locking plate 20, the lower loop 75 passing through an opening in the plate and the flexible member 10 being passed through said lower loop. Or the member may be secured to said lower loop. It will be understood that the locking plate 20 may be shaped in any suitable manner so as to engage the brooch pin sufficiently tightly to remain in position thereon. Further, that the wire loop 3 in Figs. 11, 12, 15 and the flexible member 10 in Figs. 13, 17 may be 80 used with a retaining link such as the link 7 shown in Fig. 2 for example.

It will be understood that the device constructed according to the invention is applicable to articles having securing pins other than pivoted pins, for example pins 90 having flexible hinges such as the spring coil hinge of a safety pin.

What I claim is:—

A supplemental securing device for brooches and like articles comprising in 95 combination a flexible member secured to the brooch pin by friction at one end and adapted to engage said pin at the other end, and a link secured to the article at one end and engaging the flexible member at the other 100 end, substantially as described.

In testimony whereof I have signed my name to this specification.

SAM MENDEL.

Witness:

J. HARRIS SELBLE.
